UNITED STATES PATENT OFFICE.

CHARLES E. WHITE, OF MOLINE, ILLINOIS, ASSIGNOR TO DEERE & COMPANY, OF MOLINE, ILLINOIS, A CORPORATION OF ILLINOIS.

PLANTING MECHANISM.

1,369,862.

Specification of Letters Patent.

Patented Mar. 1, 1921.

Application filed March 20, 1918. Serial No. 223,579.

To all whom it may concern:

Be it known that I, CHARLES E. WHITE, a citizen of the United States, residing at Moline, in the county of Rock Island and State 5 of Illinois, have invented certain new and useful Improvements in Planting Mechanisms, of which the following is a specification, reference being had therein to the accompanying drawing.

10 This invention relates to improvements in corn planting mechanisms; particularly to improvements in the devices for separating kernels singly from a miscellaneous mass in a receptacle and delivering them singly 15 either directly to the ground or to an accumulator wherein the kernels are collected up to a predetermined number and then deposited as a "hill" in the ground.

20 The object is to provide a rotary plate structure with single kernel cells, whose length dimensions can be varied without affecting their depth dimension or their width dimension (measured radially); and maintain the advantageous features which I have 25 introduced into such plates by which the kernels in the bottom of a mass are induced to assume flatwise positions before reaching the cells, and are compelled to tilt into edgewise positions, vertically, without 30 bridging over the cell mouths.

Figure 1 is a plan view of the parts at the bottom of a seeding mechanism embodying my improvements;

35 Fig. 2 is a bottom plan view of the two part plate element detached;

Fig. 3 is an edge view of part of this plate element;

Fig. 4 is a vertical longitudinal section on the line 4—4 of Fig. 1.

40 Figs. 5 and 6, respectively, show fragmentary parts of the peripheral portions of the seeder plate elements.

Fig. 7 is a vertical section through the upper plate element on the line 7, 7, Fig. 5.

45 Fig. 8 is a vertical section through the said element, taken on the line 8, 8 of Fig. 5.

The corn is carried in charges or small quantities in a can or receiver 1. This at its lower edge is secured tightly to a ring having the upper part 3 which slopes inwardly and the bottom vertical part 4, these constituting the outer wall of the passage or channel for the seed. The central cap part 5 is preferably formed integral with this outer 55 ring 3, there being arches 6, 7 connecting the

two parts together. The ring is also cast with hinged ears 8 by which it is hinged to a pin 9 supported on the base structure below the seed delivering mechanism and which may be of any well known sort.

60 The seed plate is positioned below the cap 5. It rests upon the ring plate 10, which in turn is supported on the base structure.

Power is transmitted to the seed plate from the shaft 11 through the pinion 12 and 65 the ring 13, having gear teeth 14. This gear ring has upwardly extending projections 13^a which engage with downwardly turned projections 22^a on the upper element of the 70 seeder plate.

The plate rests loosely in the space between the horizontal planes of the top of the ring 10 and the bottom of the cap 5, and inside of the ring 3, 4. It is formed in two parts, one indicated by 15 and the other by 75 16. The part 15 is formed with an upper narrow horizontal flange 17, a downward and outward tapering flange or wall 18 and a bottom narrow, horizontal flange 19. It is also formed with a hollow circular flange 80 or boss 20 which fits loosely but snugly in the substantially circular flange or boss 21, integral with and extending down from the stationary cap 5. This boss or circular flange 20 centers the plate in relation to the 85 ring 3, 4 and prevents the bottom horizontal part or seed separating part of the plate from crushing kernels between its edge and the stationary ring wall 4.

The boss 20 is carried by two narrow intersecting arms 22 cast integral with the upper horizontal part 17. These intersecting parts 22 carry also a downwardly extending tube or boss 23 to serve as part of the joint between the two sections of the 95 seeder plate.

The lower horizontal part 19 of the upper plate element 15 is of peculiar conformation being shaped to have a relatively thick part 24 with an approximately radial and vertical edge 25 at the rear end of each cell 26. The cells are each adapted to take one kernel only and to have the kernel stand on edge with its flat faces vertical. There are sixteen of these cells in the construction shown, this 100 number, however, being variable to correspond with different gearing to vary the number of kernels delivered at each planting action, or for other reasons.

105 The kernels at the bottom of a corn mass 110

all tend to take a flatwise position horizontally. That is to say, those that reach, and are pressed upon the cap 5 tend to rest upon it on their flat faces, and to slide from it onto the inclined wall 18 of the upper section 15 of the plate. Those which travel directly downward from the mass to this inclined wall 18 also tend to rest upon it flatwise. When this inclined wall is rotating it 10 assists in agitating the lowermost stratum of kernels, and assists them in assuming the flatwise position as they approach the cells; but as the horizontal cross dimensions of the cells are considerably less than the horizontal 15 dimensions of the kernels in flatwise position, they must be induced to depart from that position, in order to settle edgewise in the cells. Otherwise they will bridge across the upper ends of the cells, and being held 20 under the weight of the superincumbent kernels will refuse to drop into them and prevent adjacent kernels from so dropping.

I chamfer, relatively deeply, the upper surface of the bottom flange-like element 19 at 25 points adjacent the rear end of each cell, as shown at 27, this commencing at the inner end of the radial vertical edge 25 and extending to the other end of the cell. And I also chamfer or bevel off less deeply the 30 metal of the horizontal part 19 at points near the front end and in advance of this cell as at 28, the surfaces 27 and 28 being substantially continuous. When a kernel moving flatwise down the inclined surface of 35 18 reaches the sharply angled surface 27, 28, it is prevented from bridging across the cell, and its outermost edge drops under the pressure of the kernels above it, and it settles edgewise into the cell. The rear edge 40 wall 25 of the cell is, vertically, of approximately the same width as the corn kernel and the latter is, while riding on its lower narrow edge, pushed by the wall 25 around to and then under the cutoff 29 and to the 45 drop aperture under the knock-out at 30. This wall 25 at the end of the cell is a continuation of and integral with a wall 25^a, which extends along the inner edge of the cell. And these wall sections 25, 25^a extend 50 vertically continuously from the lower part 19 of the upper plate section to the bottom of the cell, that is, to the bottom horizontal plane of the seeds when in the cell. There is thus furnished a continuous smooth surface at the inner side and at the end of each 55 cell for contacting with the seed which enters it. Between each downward extending wall section 25, and the end of the next wall section 25^a, there is an open space 25^b.

60 A peculiar fact concerning all of the species of corn that are largely used through the corn belt of the United States is that while some of the kernels taken from any given ear may, in width, vary from others 65 from the same ear to the extent of several

hundredths of an inch, and those of one species may similarly, in width, vary from the kernels of another species, the kernels from all of the ears of the species, and the kernels of the various species are, within one 70 or two hundredths of an inch, or thereabout, similar to each other in their shortest, that is, their thickness, dimension. Hence, as is now well known the widths, radially, of the cells 26 are substantially the same in all 75 seeder plates for corn planters because of the apparent uniformity in thickness of all corn kernels used in planting. And it is also known that the kernels of the various sorts and conformations vary in their width 80 dimension only from 1 to 5 or 6/100 of an inch. Hence if they were all equal in the length dimension a seeder plate having the characteristics of structure above described, and having cells of an approximately fixed 85 length would be sufficient to insure, practically, that each cell would carry one kernel to the delivery point at 30.

But experience shows that the kernels of one mass or charge in a receptacle, in their length dimension vary considerably from those in another mass or charge therein; and that those in a mass of one species of corn may vary from those in another mass; and that the kernels of a given species may, if grown in one season, differ in their length dimensions from those grown in another season. And because of these facts the cells of a seeder plate require one length dimension to meet one set of conditions and another to meet other conditions.

Heretofore, this matter has been met by providing a relatively large number of plates for each planter machine. Each of these plates is similar to the others so far as concerns the radial width of the cells and as concerns the devices for inducing the wider kernels and the narrow ones (considering their flat faces) to all enter the same cells; but each plate has differed from the others in the matter of the length of the cells, some being designated as "small;" others as "medium" and others as "large," these terms meaning that the plates are similar to each other as concerns the cells, except in respect to the length dimension.

At least six plates must be furnished with each machine to meet these variations.

One of the objects of the present invention being to reduce the number of parts in, and the cost of a planting mechanism, and to simplify the apparatus, I furnish one set of plates to meet all variations in the kernels.

As already remarked each seeding plate is made in two sections, 15, and 16, the section 15 having been above fully described. The lower section 16 is in the form of a plate 31 with diametric bars 32 intersecting at the center and peripheral projections or teeth 33. At the center there is formed an 120 125 130

integral circular flange or hollow boss 34. It fits snugly but rotatably around the sleeve or boss 23 on the upper section 15 of the plate. The two sections are rigidly clamped by a central bolt 35, whose head and nut 36 tightly bind them together, the head bearing against the upper section and the nut 36 against the lower. If the nut 36 is loosened, these sections 15 and 16 can be rotated, more or less, for adjustment, and then again rigidly clamped together. The number of the peripheral projections or teeth 33 is equal to the number of the cells. Each tooth is of a total width, peripherally, equal to or less than the width of each tooth-like part on the upper section 15, that is, each projection between the radii of the edges 25 and 37. Between each tooth 33 and the next there is a peripheral recess in the lower section which extends in to the edge 38, positioned well inside of the inner edge of the cell in the upper section 15, so that the metal of the lower section 16 will not modify the width of the cell, under any adjustment of the sections. Again, each tooth 33 is formed with a peripheral projection 39, which can be held positioned under the metal constituting the tooth-like projection on the upper section, or can be adjusted so as to extend peripherally backward from the front end edge 40 of a cell in the upper section.

That is to say, the peripherally projecting parts 39 on the teeth 33 of the lower plate section 16 can all be set so as to shorten the length dimension of each of the cells measured forward from the edges 25 on the tooth-like parts of the upper section. Each of these teeth 33 and its projection 39 extend through one of the wall spaces 25^b between a wall section 25 and the adjacent wall section 25^a on the upper plate section, and all of the teeth lie in the horizontal planes of said wall sections.

If the kernels in the mass in the receptacle or hopper are, generally throughout the mass, longer or shorter than the kernels of another mass, the devices described furnish provision for so fixing the length of the cells that they shall compensate for this difference in the average length of the kernels. After loosening nut 36 the lower section can, relatively to the upper section, be moved forward in relation to the direction of rotation, or backward a few hundredths of an inch, measured at the periphery; and in this way cells can be provided which will receive the kernels without an unfilled or unoccupied space being left at either end of a cell wherein the point parts of kernels can wedge or enter.

I am aware that two part plates have been proposed for varying the length dimensions of the seed cells. But, I believe myself to be the first to have provided a seeder plate

which is constructed to furnish the relatively long tapered or sloping wall 18 adapted to induce the kernels in the peripheral part of the lower stratum of the mass to take a flatwise position at points near the cells; and to have introduced devices, such as the cutaway surface at 27, 28, to prevent the kernels from bridging flatwise across the narrow cell mouths; and then while retaining the standard dimension, radially considered, for the cell, to have made provision for preventing the occurrence of unoccupied regions in the cells at the ends when the kernels are relatively short; said plate mechanism being adapted for use both in planting relatively long kernels and in planting those that are relatively short.

What I claim is:

1. In a corn planting mechanism, a rotary two section seeder plate having at the periphery seed cells each open at the outer side, and each having a vertically continuous wall extending from the bottom to the top of the cell along the inner side thereof, and at the end, the upper section of the plate being integral with the said vertical walls, and the lower section having a series of relatively backward extending projections in the horizontal planes of the said walls and said lower section being adjustable to vary the positions of said projections relatively to the ends of the cells in the upper section to vary the length dimensions of the said cells.

2. In a corn planting mechanism, a rotary two section seeder plate, the upper section having outwardly open seed cells in its periphery, each cell having at the inner side and at one end a vertical wall extending continuously from the upper section to the bottom plane of the seeds when in the cells, and the lower section having a series of projections at its periphery adapted to be adjusted lengthwise of the cells and positioned in the horizontal planes of the said walls.

3. In a planting mechanism of the class described, the combination with the receptacle and the stationary bottom structure having an approximately vertical wall, of a two section seeder plate of which the upper section is formed with peripheral cells closed at their outer sides by the said stationary wall and each cell having at its inner side and at its rear end a vertical wall integral with the upper section, and the lower section having peripherally adjustable backward extending projections adapted to be adjustably moved past the last said cell walls to vary the length dimension of the cells.

4. In a corn planter, a seed plate having the outward sloping element 18 and the integral bottom flange-like element 19 formed with peripheral cells each adapted to hold a single corn kernel edgewise and

having at its rear end a vertically thick kernel-engaging part 24, the upper surface of the bottom flange element, at the inner edge of the cell, being chamfered relatively 5 deeply as at 27 at points adjacent the rear end of the cell and less deeply at 28 at points near the front end of the cell, the cham-

fered surface being adapted to tilt kernels to vertical positions edgewise, after being partially tilted by the sloping element 18, substantially as described.

In testimony whereof I affix my signature.

CHARLES E. WHITE.
